UNITED STATES PATENT OFFICE.

CHARLES W. SHONK, OF MAYWOOD, ILLINOIS, ASSIGNOR TO CHARLES W. SHONK COMPANY, OF CHICAGO, ILLINOIS, A CORPORATION OF NEW JERSEY.

SHEET-METAL MATCH-STAND AND BURNT-MATCH HOLDER.

1,087,147.

Specification of Letters Patent.

Patented Feb. 17, 1914.

Application filed October 23, 1909. Serial No. 524,159.

To all whom it may concern:

Be it known that I, CHARLES W. SHONK, a citizen of the United States, residing in Maywood, in the county of Cook and State 5 of Illinois, have invented a new and useful Improvement in Sheet-Metal Match-Stands and Burnt-Match Holders, of which the following is a specification.

My invention relates to sheet metal match 10 stands and burnt match holders.

The object of my invention is to provide a sheet metal match stand and burnt match holder of a simple, efficient and durable construction capable of being cheaply manufactured, which will set firm and stable in 15 position, which will have both a scratch surface and an ornamental surface for receiving any desired decoration, and from which the burnt matches may be conveniently and easily removed.

My invention consists in the means I employ to practically accomplish this object or result, as herein shown, set forth and described, and more particularly specified in 25 the claim.

In the accompanying drawings forming a part of this specification, Figure 1 is a side elevation of the sheet metal match stand and burnt match holder embodying my invention; Fig. 2 is a central vertical section on line 2—2 of Fig. 1; Fig. 3 is a horizontal section on line 3—3 of Fig. 2; and Fig. 4 is a detail bottom view of the weight disk.

In the drawing, A represents the sheet 35 metal bottom or base, the same having a raised or dome shaped center a surrounded by a horizontal flange a¹ terminating in a conical flange a² which is provided with a seaming flange a³, which is folded or seamed 40 over the flange b at the lower end of the tapering or conical burnt match holding member B.

The raised upwardly projecting center a of the base A forms a chamber or recess to 45 receive the weight C preferably of iron and which is secured to the base A in said recess by a screw or bolt C¹ having a slotted head C² and a nut C³ which fits in a recess C⁴ in the lower side of the weight disk C.

50 The weight disk serves to give stability and firmness to the match stand. The tapering or conical sheet metal body B has a folded or locked side seam b¹ uniting its

meeting edges and a plurality of large openings B¹ through which the burnt matches 55 may be inserted into the burnt match holding chamber B². The sheet metal body B is made of ornamental or decorated sheet metal, preferably tin plate. The outer or 60 ornamented surface b² of the body B is preferably decorated by printing or photolithographing, while the sheet or blank from which the body is formed is in the flat.

The scratch member D of the match stand is preferably formed in a separate piece 65 from the decorated member B, and preferably of sheet brass, the same being seamed or connected at its lower end to the upper end of the member B by interengaging annular seaming flanges or beads b³ on the 70 member B, and d on the member D. The scratch surface d¹ of the scratch member D is preferably made up of annular corrugations d² formed in the sheet metal. The scratch member D as well as the body B are 75 preferably of a flaring or truncated cone shape, and both are preferably made of the same flare or taper.

The sheet metal scratch member D is provided at its upper end with a horizontal 80 flange d³ terminating in a depending flange d⁴ forming a socket to receive the match container F which is likewise of sheet metal, preferably sheet brass, the same being preferably seamless and drawn up out of one 85 piece and provided at its upper end with an annular roll f adapted to rest upon the horizontal flange d⁵ of the scratch member D.

To empty the burnt matches from the 90 burnt match chamber B², the removable match container F is first removed and then the stand is inverted and the burnt matches discharged through the open mouth of the scratch member D.

95

I claim:

A match stand and burnt match holder comprising a hollow sheet metal rigidly formed main member having a raised base portion and a central opening in its top, and 100 tapered from the base portion to the top, and having an opening in the lower portion of the tapered sides for burnt matches, and provided also on the tapered sides at the upper portion with horizontally extending 105 corrugations forming a scratch surface, a

weight disk secured in the raised base portion, means for securing said disk in place and a match container having an annular rim resting on the top of the main member and removably fitting within the top opening of the main member, whereby the central opening is closed when the container is

in place and the burnt matches may be removed and access had to said means when the container is removed.

CHARLES W. SHONK.
